UNITED STATES PATENT OFFICE.

JAMES BROPSOM, OF CLEVELAND, OHIO.

PLUMBER'S FURNACE.

1,253,778.

Specification of Letters Patent. Patented Jan. 15, 1918.

Application filed May 13, 1916. Serial No. 97,251.

To all whom it may concern:

Be it known that I, JAMES BROPSOM, a citizen of the United States of America, residing at Cleveland, in the county of Cuyahoga and State of Ohio, have invented certain new and useful Improvements in Plumbers' Furnaces; and I hereby declare the following to be a full, clear, and exact description of the invention, such as will enable others skilled in the art to which it pertains to make and use the same.

This invention relates to new and useful improvements in plumbers' furnaces.

One object of this invention is to provide a furnace of this character which can be readily assembled and easily taken apart for cleaning or repair.

My invention therefore consists in the features of construction and combination of parts hereinafter described in the specification, pointed out in the claims and illustrated in the accompanying drawings.

Referring to the accompanying drawings, Figure 1 is a view in elevation showing a furnace embodying my invention. Fig. 2 is a section on line 2—2, Fig. 1. Fig. 3 is a section on line 3—3, Fig. 1.

Again referring to the drawings, 3 represents the base of the furnace which is made hollow so as to serve as a receptacle for the gasoline or similar fluid which is to be employed as the fuel for the furnace. In the top of this receptacle is formed a filling opening 4 which is closed by means of a plug 5 in the usual manner. On the top of the receptacle is also mounted a small pump 6 of the usual construction for creating an air pressure within the receptacle. On top of the receptacle are formed a series of bosses 8, and these bosses are drilled and tapped with a right hand thread. In each of the bosses is screwed a supporting rod 10 which is provided with a thread corresponding to the thread in the boss. On top of the rods 10 is arranged an annular supporting head member 12 which is provided on its under surface with three bosses 13, and these bosses are drilled and tapped with a left hand thread and are arranged to receive the upper ends of the rods 10 which are threaded correspondingly. It will therefore be seen that the head member 12 can be readily and rigidly secured to and supported above the base member by simply turning the rods 10 as the lower ends will screw down into the tapped bosses on the base, and the upper ends of

said rods will screw up into the bosses 13 on the head member. The opening in the head member 12 is shown at 14, and from the under surface of said head member is a downwardly extending flange 15. On the upper surface of the head member 12 are formed a series of hook shaped members 16. On top of the head member is mounted the bowl 17 which has an opening 18 in the bottom thereof corresponding to the opening in the head member 12. The bowl is provided with a small bottom flange 20, which engages with the hooks 16 in a known manner. On the inside of the bowl are formed a series of ribs 22. The ladle is shown at 23 and is preferably provided with a bail shown at 24. On the side of the ladle are formed a series of slotted ribs 25 which are adapted to register with and receive the ribs 22 on the inner surface of the bowl of the furnace, whereby the said ladle is supported within the bowl and spaced from the sides thereof, while at the same time the ladle is held firmly against movement.

On the top of the receptacle 3 is mounted a small boss of base member 28 in which is a socket 29. The lower end of a standard 30 is inserted in the socket 29 and is locked therein by means of a pin 40. The upper end of the standard is provided with a circular head 41. On the head 41 is mounted an inverted conical shaped shield 42, the upper end of which is arranged to receive the flange 15 on the bottom of the head member. The shield 42 is provided with the usual perforations 43. The fuel pipe is shown at 45 and the pipe is provided with a valve 46, and between the valve and one section of the pipe 45 is a union member 47 which permits the pipe to be separated above the valve so as to allow the ready removal of the vaporizing coil 49 without removing the head member of the furnace. The burner section 50 is provided with an extension 51 by means of which it may be screwed out of the end of the vaporizing coil.

When using furnaces of the character indicated, it becomes necessary at times to renew the vaporizing coil, and with the types of furnaces now on the market it is practically necessary to take the whole device apart in order to remove the coils. With my arrangement, when it is necessary to renew a coil, in order to remove the old coil, it is only necessary to first unscrew the burner 51, then loosen the union joint 47,

after which the pin 40 is withdrawn from the boss 28, which permits the standard 30 to be taken from under the shield 42, which will then slip down leaving the coil exposed.

5. What I claim is:—

1. In a furnace of the kind described, the combination of a base, a head supported above said base, said head having an opening and a depending flange around said opening, 10 a standard removably supported on the base, and a shield supported on the standard and having its upper end engaging the said flange.

2. In a plumber's furnace, the combination of a base member forming an oil receptacle, supporting rods extending up from the base member, a head member mounted

on the upper ends of the supporting rods, said head member having a circular opening and having a flange extending down through 20 the under side thereof around said opening, a boss arranged centrally on the top of the receptacle, a standard removably mounted in said boss and a shield arranged to rest on the top of said standard and having its 25 upper end engaging the flange on the head member.

In testimony whereof, I sign the foregoing specification, in the presence of two witnesses.

JAMES BROPSON.
